DRY-PIPE VALVE.

Application filed October 25, 1924. Serial No. 745,774.

This invention relates to dry pipe valves such as are used in so-called "dry pipe sprinkler systems." In such sprinkler systems the sprinkler pipes are filled with air under pressure and the flow of water to the sprinkler system is controlled by a dry pipe valve which is normally held closed by the pressure of the air in the system but which opens to allow water to flow into the system when the air pressure in the system falls below a predetermined point by reason of air escaping from a sprinkler head which has given way or from any other cause.

When a sprinkler head in a dry pipe system opens by reason of a fire or otherwise the air in the system immediately begins to escape and the air pressure begins to fall but an appreciable time interval will elapse before the pressure has fallen sufficiently to allow the dry pipe valve to trip. The length of such time interval will depend upon the volume of air in the system and, therefore, in a large system having the maximum number of sprinkler heads allowed by insurance regulations the time interval between the giving way of a sprinkler head and the opening of the dry pipe valve will be greater than in the case of a small system having relatively few sprinkler heads.

In the case of a fire it is, of course, important to have the water reach the sprinkler head which has given way with the least delay possible and in order to minimize this time interval there have been produced so-called "dry pipe valve accelerators" which have for their object to accelerate the opening of the dry pipe valve after a sprinkler head has given way. While these dry pipe valve accelerators are effective in reducing the time interval between the giving way of a sprinkler head and the opening of the dry pipe valve, yet their installation involves considerable added expense, and introduces objectionable features.

A dry pipe valve and the pipe connection and trimmings therefor constitute one of the expensive elements of a sprinkler system, and for this reason it is customary to load each dry pipe valve with as large a number of sprinkler heads as will be allowed by insurance regulations.

It is one of the objects of my present invention to provide a novel dry pipe valve which will accommodate the maximum number of sprinkler heads allowed by insurance regulations, but which will supply water at

any head when said head opens much more quickly than the usual dry pipe valve for the same number of heads.

As one means towards accomplishing this end I use a dry pipe valve with a single inlet and with two separate outlets, which dry pipe valve is provided with a water valve and a corresponding air valve for controlling the flow of water through each outlet. In using this dry pipe valve I propose to subdivide the portion of the sprinkler system to which the valve is connected into two sections and connect one section to each outlet of the dry pipe valve. With such an arrangement the valves controlling both branches of the inlet will be held closed so long as there is normal air pressure in both sections of the system, but if a sprinkler head in either section gives way the corresponding reduction of air pressure in said section will result in the tripping of the corresponding valve, thus allowing water to flow to that section of the system in which is located the opened sprinkler head.

The two sections into which the system controlled by the dry pipe valve is subdivided are independent from each other, so that the opening of a sprinkler head will admit water to that portion only of the system on which the opened sprinkler head is located. By thus subdividing the system the volume of air in each section thereof is, of course, considerably less than the volume in the entire portion of the system controlled by the dry pipe valve and, therefore, the time interval between the opening of the sprinkler head and the tripping of the valve is correspondingly reduced. By means of my improved dry pipe valve the reduction in the time interval elapsing between the giving way of a sprinkler head and the admitting of water to the system by opening the dry pipe valve is gained without the use of a dry pipe accelerator and at an expense which is not materially greater than that involved in installing a dry pipe valve as now commonly made.

Dry pipe sprinkler systems are usually installed in locations that are subjected to freezing temperatures and an advantage resulting from my invention is that when a sprinkler head opens the water will be admitted only to that division of the system in which the open sprinkler head is located, thus avoiding the danger of having the entire system frozen up in cold weather, which ex-

ists where the water is admitted to those portions of a large system remote from the opened sprinkler head and where there was no call for water.

As a further improvement, and to avoid water columning I propose to employ a valve structure for the water valve and air valve, which is so constructed that when surrounded by air it will be held to its seat by gravity. But when the valve is near the critical tripping point and the neutral chamber is filled up with water so that the valve structure is surrounded by water, the position of the center of gravity of the valve structure will change sufficiently to bring it to a point at which the valve will tend to open by gravity. This change in the position of the center of gravity of the valve structure at the critical point facilitates the opening of the valve, so that the valve will open before a sufficient amount of water can pass by the air clapper to water column the valve.

In order to give an understanding of the invention I have illustrated in the drawings a selected embodiment thereof which will now be described after which the novel features will be pointed out in the appended claims.

Fig. 1 is a sectional view through a dry pipe valve embodying my invention;

Fig. 2 is a view illustrating an installation of a dry pipe valve embodying my invention.

Referring first to Fig. 2, 1 indicates generally a sprinkler system having sprinkler pipes 2 and 2^a carrying sprinkler heads 3. Although this sprinkler system is shown diagrammatically it may be assumed that the number of sprinkler heads therein is the maximum number allowed by insurance regulations for any one dry pipe valve.

In carrying out my invention I subdivide the system into two divisions and provide a riser for each division. Merely as an illustration of this, I have shown in Fig. 2 the upper two sprinkler pipes 2^a which might be those of the upper stories of a building, connected to one riser 4^a the lower two sprinkler pipes 2 which might be those in the lower stories of a building, connected to the other riser 4, so that part of the sprinkler pipes are fed from one riser and part from the other.

My improved dry pipe valve is provided with an inlet communicating with the water supply system and with two outlets communicating with the two risers 4 and 4^a, and it is so constructed that if a sprinkler head in either subdivision of the system gives way water will be admitted to that subdivision of the system only, the air pressure being retained in the other subdivision of the system.

The dry pipe valve herein shown comprises a casing 5 which has the single inlet 6 that

is connected to a water supply pipe. This inlet is of the size required by the maximum number of sprinkler heads to be supplied by the risers 4 and 4^a. The two outlets of the dry pipe valve are indicated at 8, one being connected to each of the risers 4 and 4^a, as stated above. The interior of the casing is divided into two chambers 9 and 10 and the inlet 6 is branched as shown at 11 and 12, one branch leading to each of the chambers. The branches 11 and 12 terminate in valve seats 13, 14 on which are seated water valves 15, 16.

Each water valve has associated with it an air valve, the latter being designated at 17 and 18 respectively. These air valves are pivotally mounted within the casing, the air valve 17 being pivoted at 19 and the air valve 18 being pivoted at 20. Situated within the chamber 9 is an annular valve seat 21 on which the air valve 17 seats and in the chamber 10 is a similar valve seat 22 on which the air valve 18 seats.

In the present embodiment of the invention the branches 11, 12 of the inlet diverge from each other so that the water valve seats 13, 14 each have an angular relation. The air valve seats 21, 22 are parallel to the valve seats 13 and 14 and, therefore, the water valve and air valve comprising each valve structure are parallel to each other. Each water valve may be connected to its air valve in any suitable way as by means of a bolt or screw 23.

The casing 5 is divided by partitions 24, 25 to form a neutral chamber between each air valve and the corresponding water valve which is open to the atmosphere, these neutral chambers being designated at 26 and 27 respectively. Each neutral chamber will be provided with a suitable drip valve, not shown, as usual in dry pipe valves.

In the operation of the device both valves will be normally closed and will be held closed by the pressure of the air against the air valve so long as the air pressure in the system is normal.

But if, for instance, a sprinkler head in one of the sprinkler pipes 2^a gives way the air in the subdivision of the system including said sprinkler head will escape and when the pressure has been reduced to a predetermined point the valve which is connected to the riser 4^a leading to the sprinkler pipes 2^a will trip, thus allowing water to flow to the open sprinkler head. The reduction of the pressure in the sprinkler pipes 2^a will not, however, affect the pressure in the sprinkler pipes 2 so that the water will only be delivered to that section of the system in which the open sprinkler head is located. The time interval required for a reduction of the air pressure in the section 2^a to a point where the valve will trip is very much less than would be required to secure the same

reduction of air pressure throughout the entire system and as a result of this arrangement the time interval elapsing between the opening of a sprinkler head and the flow of water therefrom is materially reduced, which is highly important in case of a fire. Moreover, since the opening of a sprinkler head will admit water to that section only of the system in which said sprinkler head 10 is located there is no danger of a freeze-up occurring in cold weather in other sections of the system remote from the open sprinkler head and where water is not needed.

In the installation of a dry pipe valve 15 the pipe connections and trimmings form a very substantial part of the expense and with the present duplex valve structure the expense for pipe connections and trimmings is just about the same as it is for the dry 20 pipe valves now commonly used, so that the cost of installation of my improved duplex valve is substantially the same as that of an ordinary dry pipe valve.

As a further improvement in the dry pipe 25 valve, I make provision for avoiding water columning of the valve—that is, the accumulation of water above the air clapper without the valve opening. This is accomplished by providing means for maintaining 30 the center of gravity of the valve when surrounded by air, on the valve side of the pivot about which valve swings and for shifting this center of gravity to the other side of pivot when valve is entirely surrounded by water, which would be the case 35 when the valve is near the tripping point.

This shifting of the center of gravity may be accomplished in various ways. The selected way as shown herein is to form a 40 chamber in the air clapper and fill the same with a substance having substantially the same specific gravity as water.

When the valve is set ready for operation 45 the space immediately above the air clapper contains priming water, while the neutral space below the air clapper is filled with air at atmospheric pressure. When the pressure in the system is reduced to substantially the point at which the air valve 50 will trip, then the valve structure will begin to flutter and water will accumulate in the neutral chamber, so that at the time the valve trips there is water in the neutral chamber and the air valve has water on both sides 55 thereof.

The chamber in the air valve which is 60 filled with this material having substantially the same specific gravity as water, is so located that under normal working conditions when the neutral chamber is filled with air the center of gravity of the valve structure will be on the side of the pivot toward the valve seat, and the action of gravity therefore will tend to hold the valve seated. 65 When the critical tripping point is about

reached and the neutral chamber is filled with water, then because of the fact that the material in the chamber of the valve has substantially the same specific gravity as water, said material will cease to have any 70 valve-closing effect, and as a result the center of gravity of the valve will shift to the opposite side of the pivot.

Referring to the drawings it will be noted that the air valve 18 is provided with a 75 chamber 32 which is filled with some material 31 such, for instance, as a suitable wax, that has substantially the same specific gravity as water. The valve structure 18 without the material 31 is so designed that 80 the center of gravity thereof is at the right of the pivot 20, and hence if the material 31 were removed from the chamber the valve would tend to open by gravity.

So long as the neutral chamber 27 is filled 85 with air, so that the valve 18 has water on its upper side only, the material 31 adds its weight to the weight of the valve 18, tending to hold the valve closed, and under these conditions the center of gravity of the combined air and water valve will be at the left 90 of the pivot 20, so that the action of gravity tends to hold the valve closed.

When, however, the air and water valve 95 structure is entirely immersed or submerged in water or a pressure having the same specific gravity as that of the material 31, which will be the condition when the valve structure is about to trip and the neutral chamber 27 is filled with water, then the material 100 31 ceases to act as a weight, because it has substantially the same specific gravity as water, and the effect is the same as if the material 31 had been removed from the chamber 32. 105

Therefore, under the conditions the center of gravity is shifted to the right of the pivot 20 and the valve tends to open by gravity. This construction, therefore, facilitates the opening movement of the valve 110 at the tripping point, and avoids water columning.

With my invention, therefore, I have provided for shortening the time interval between the giving way of a sprinkler head 115 and the flow of water therefrom without materially increasing the cost of installation and I have further improved the valve by providing novel means for avoiding the water columning thereof. 120

I claim:

1. A duplex dry pipe valve comprising a casing divided into two chambers each having its own outlet, said casing having a single inlet which is branched with one 125 branch leading to each chamber, a separate water valve for closing each branch, an air valve for each water valve, each air valve being subjected only to the air pressure in the corresponding valve chamber 130

and operating to hold the corresponding water valve closed, said casing having two separate neutral chambers, one between each water valve seat and the corresponding air valve seat.

2. In a dry pipe valve, a casing having a waterway and a valve structure adapted to close the waterway and comprising a water valve and an air valve, there being a neutral chamber between said valves, said valve structure being so constructed that the action of gravity thereon will tend to hold it closed when the neutral chamber is filled with air and will tend to open it when said chamber is filled with water.

3. In a dry pipe valve, a casing having a waterway and a pivotally-mounted valve structure adapted to close said waterway and comprising a water valve and an air valve arranged with a neutral chamber between them, said valve structure having a pocket filled with material having substantially the same specific gravity as water, said pocket being so located relative to the pivot of the valve structure that when the neutral chamber

is filled with air the action of gravity on the valve structure tends to hold it closed while when said chamber is filled with water the center of gravity of the valve is shifted to a point at which the action of gravity tends to open the valve structure.

4. In a dry pipe valve, the combination with a casing having a waterway, of a water valve to close said waterway, a pivotally-mounted air valve to hold the water valve closed, said casing having a neutral chamber between said valve, said air valve having a pocket filled with material having substantially the same specific gravity as water, whereby when the valve structure is entirely surrounded with water by reason of the neutral chamber being filled, the center of gravity of the valve will shift from a position in which the action of gravity tends to hold the valve closed to a position in which said action tends to open the valve.

In testimony whereof, I have signed my name to this specification:

EZRA E. CLARK
